UNITED STATES PATENT OFFICE

123,613

DESIGN FOR A LACE OR SIMILAR ARTICLE

David Edelstein, Brooklyn, N. Y.

Application October 12, 1940, Serial No. 95,824

Term of patent 3½ years

To all whom it may concern:

Be it known that I, David Edelstein, a citizen of the United States, residing in Brooklyn, N. Y., county of Kings and State of New York, have invented a new, original, and ornamental Design for a Lace or Similar Article, of which the following is a specification, reference being had to the accompanying drawing, forming a part thereof.

The figure of the drawing is a plan view of a lace or similar article, showing my new design.

I claim:

The ornamental design for a lace or similar article, as shown.

DAVID EDELSTEIN.
